CLAIM

The ornamental design for a housing for an electric hair clipper, as shown and described.

DESCRIPTION

FIG. 1 is a perspective view of a housing for an electric hair clipper, depicting an embodiment of the present invention; FIG. 2 is the rear view of the housing of FIG. 1; FIG. 3 is the front view of the housing of FIG. 1; FIG. 4 is the right side view of the housing of FIG. 1; FIG. 5 is the left side view of the housing of FIG. 1; FIG. 6 is the top view of the housing of FIG. 1; FIG. 7 is the bottom view of the housing of FIG. 1; FIG. 8 is a perspective view of an attachment that attaches to the housing of FIG. 1; FIG. 9 is the rear view of the attachment of FIG. 8; FIG. 10 is the front view of the attachment of FIG. 8; FIG. 11 is the right side view of the attachment of FIG. 8; FIG. 12 is the left side view of the attachment of FIG. 8; FIG. 13 is the top view of the attachment of FIG. 8; and, FIG. 14 is an exploded view of the housing of FIG. 1 attached to the attachment of FIG. 8. The broken lines illustrate portions of the housing and form no part of the claimed design.
